UNITED STATES PATENT OFFICE.

IRVING E. ASKE, OF DULUTH, MINNESOTA.

FUEL-VAPOR CONDUCTOR FOR INTERNAL-EXPLOSION ENGINES.

Application filed August 26, 1922. Serial No. 584,449.

To all whom it may concern:

Be it known that I, IRVING E. ASKE, a citizen of the United States, residing at Duluth, in the county of St. Louis and State of Minnesota, have invented certain new and useful Improvements in Fuel-Vapor Conductors for Internal-Explosion Engines, of which I do declare the following to be a specification.

10 My invention relates to fuel vapor conductors for internal explosion engines and has for its object the provision of means for deflecting into the stream of vapor the films of liquid which tend to cling to certain walls of the carburetor throat and of the manifold and to flow into the cylinders in liquid form. Such tendency is especially apparent in low grade gasoline and is facilitated by curved bends which the rapidly flowing film of liquid can follow. One of the objects of my invention is to introduce sharp angular turns at certain turning points in the course of such conductor or films so that the films will be cut and drawn off into the stream of vapor and broken up and vaporized. A further object is to provide riffle plate or ribs in said conduit to deflect said films into the stream of vapor.

20 In the drawings, Fig. 1 is a side elevation partly in central vertical section of a carburetor throat, a vaporizer housing and a manifold embodying my said invention. Fig. 2 is an end elevation of the same partly in section on the line A—B of Fig. 1. Figs. 3, 4, 5 and 6 are central transverse sections through different forms of the hereinafter described riffle plates or ribs forming part of my said invention.

30 In the drawings, 1 is a carburetor throat; 2 is a housing for the reception of a heating device (not shown) and 3 is a manifold, each forming part of a conductor for fuel

vapor from a carburetor (not shown) to engine cylinders (not shown), and 4 is a boss.

45 In constructing said throat and manifold I form sharp angular turns at the inner bends of the conduit as at 3^a, so a rapidly flowing film of liquid instead of flowing around the turn in adherence to the wall 50 will be drawn or shot off into the adjacent stream of vapor and there thoroughly mixed and vaporized. Upon the inner faces of the outward bends of said conductor and at such other points, if any, as may be desired, as 55 3^b, 3^c, 3^e, 3^f, I form riffle plates or ribs of any suitable form, as 3^g, 3^h, which extend transversely of the conduit across the path of the liquid film. Said ribs are preferably crescent shaped transversely of the conduit 60 and thinner at their ends than in their centers. Where such ribs appear on opposite walls, they are preferably staggered with respect to each other, as at 3^c, 3^e. Said ribs may have any suitable profiles adapted 65 to deflect the film liquid from the wall into the steam of vapor, some of which forms of ribs are shown in section in Figs. 3, 4, 5 and 6.

70 It is obvious that said construction may be modified in certain particulars within the spirit and scope of my claim.

What I claim is—

75 A conductor for fuel vapor comprising a tube having a segmental transversely directed rib formed upon the inner face of the tube wall, said rib being reduced in depth from its center toward both ends, said said rib being thicker at its attached edge than at its free edge and extending only 80 part of the distance around said tube.

In testimony whereof I hereunto affix my signature.

IRVING E. ASKE.
